UNITED STATES PATENT OFFICE.

JOSEPH PERCY WILKS, OF UTTOXETER, ENGLAND, ASSIGNOR OF ONE-HALF TO
WILFRID HILL, OF BIRMINGHAM, ENGLAND.

BULLET-PROOF AND LIKE GARMENT AND COVERING FOR HORSES AND ARTICLES EXPOSED TO ACTS OF WARFARE.

1,239,329.

Specification of Letters Patent.

Patented Sept. 4, 1917.

Application filed March 1, 1917. Serial No. 151,836.

To all whom it may concern:

Be it known that I, JOSEPH PERCY WILKS, a subject of the Kingdom of Great Britain, residing at Market Place, Uttoxeter, in the 5 county of Stafford, England, have invented certain new and useful Improvements in Bullet-Proof and like Garments and Coverings for Horses and Articles Exposed to Acts of Warfare, of which the following is

10 a specification.

This invention comprises improvements in devices for protecting human beings, horses, and articles for use in warfare, and has more particularly for its purpose to withstand or 15 obstruct such flying missiles as bullets, shrapnel, and the like, and also to withstand attacks with the bayonet or the like.

The present invention comprises a bullet-proof or like garment or covering for horses 20 or articles exposed to acts of warfare, involving a base or cover of flexible material to which layers or flaps of flexible material are attached at their one edges so that the 25 said layers overlap one another, and in which the arrangement is such that not less than a plurality of thicknesses of the flap element occur all over the surface which it is desired should be puncture-proof.

The flaps or layers of the present invention 30 may be of textile fabric, the texture of which is as close or tough as possible, or such layers may be comprised of woven wire sheets, leather, or other suitable material. The layers are preferably in pieces 35 of double thickness, each formed with a fold, and which pieces are of square or oblong formation, the top of such pieces being sewn or otherwise secured to a closely woven textile or other suitable cover or body 40 in such a manner that each succeeding piece secured almost covers the preceding piece, thus providing a form of fish scale covering, of, say, a dozen double thicknesses of material at any point, thus providing a resilient, 45 elastic, or "giving" effect when struck by a bullet or other missile, with the result that the piercing of the thicknesses by the bullet is to a substantial extent obviated.

In relation to the outer or free edges of the 50 flaps or layers, two or more layers of calico or the like are incorporated. Between these layers of calico, silk or silk fabric in irregular or waste form, or cotton wool or the like,

is incorporated, the layers being quilted and being secured at their edges to the cover 55 ing. If necessary or desirable said layers may be also secured to certain or all of the flaps or layers.

In the case of the layers being of woven wire, leather, or other suitable material the 60 pieces have their one edge secured to the base or body as before described, but in such cases they are preferably not folded owing to the extra thickness of the material, or in some cases pieces or sheets of woven wire or 65 the like may be interleaved with the folds of the textile fabric.

In order that this invention may be clearly understood and easily carried into practice, reference may be had to the appended explanatory 70 two sheets of drawings, upon which:

Figure 1 illustrates in section one form of covering according to the present invention.

Fig. 2 illustrates in elevation a modification. 75

Fig. 3 is a cross-section of the modification shown in Fig. 2.

Fig. 4 is an elevation illustrating a modification in the arrangement of the layers. 80

Fig. 4^a illustrates a further modification in the arrangement of the layers.

Fig. 5 is an elevation in diagram illustrating one arrangement of wire mesh which may be secured to certain or all of the layers 85 of canvas or the like.

Figs. 6, 7 and 8 are similar elevations in diagram to Fig. 5, illustrating other arrangements of wire work.

Fig. 9 illustrates one length of the wire 90 utilized in arrangements such as shown in Figs. 5 to 8, said wire involving a wire core and another length of wire coiled around same.

In one embodiment of this invention, the 95 layers are formed of pieces of textile fabric *a*, each piece of which is folded into two, the part near the fold being sewn to the covering or base *b* of the shield or protector, in such a manner that each piece *a* overlaps the 100 previous piece in such a manner as to form a fish scale covering, the scales of which hang down and overlap one another over the whole surface of the outer cover or shield.

Two or more layers of calico or the like 105 *k* may be incorporated in relation to the

outer edges of the flaps *a*, between which layers *k*, silk or silk fabric in irregular or waste form, or cotton wool or the like *l*, may be incorporated, the layers *k* being quilted to 5 maintain the material *l* in position. Said layers *k* may be secured around their edges to the covering, and if necessary or desirable they may also be secured to certain or all of the flaps *a* at the free edges thereof.

10 Fig. 3 illustrates an embodiment in which the layers are formed of pieces of textile fabric, each piece of which is folded into two, but in which, instead of the part near the fold being secured to the covering or 15 base *b*, parts remote from the fold are secured to said covering or base.

Such overlapping pieces may extend across the whole width of the inside of the outer cover or shield, in which case, they 20 may be vertically plaited at intervals, so as to provide that amount of "give" required in a horizontal direction, or such overlapping pieces may be vertically cut at intervals for allowing of the required freedom 25 of movement, or separate overlapping pieces may be secured in horizontal rows, so arranged that the vertical divisions of one row overlap the vertical divisions of the previous row as illustrated by Fig. 4, thus forming an 30 arrangement of the pieces in which the vertical divisions lie in planes disposed obliquely to the planes of the layers, or in case of the vertical divisions between the overlapping pieces being at right angles to the 35 planes of the layers, as shown in Fig. 4^a, a second series of overlapping pieces *a*¹ secured to another textile covering *b*¹ may be so combined with the first series *a* that the vertical divisions of the one series are covered 40 by the central parts of the overlapping pieces of the other.

In some cases, pieces of woven wire, leather or other suitable material may be placed in between certain of the overlapping pieces, 45 or the overlapping pieces may be composed entirely of woven wire, leather, or other such material.

The textile material *b* to which the overlapping pieces are secured is preferably of 50 an elastic nature, and in some cases may consist of a light material, such as muslin, strengthened by strips of elastic arranged vertically, while the overlapping pieces *a* when formed of textile material may be so 55 cut on the bias of the texture as to assist in that elasticity or resiliency which is required in connection with this invention.

In connection with such layers of fabric, 60 a further series of layers or folds of fabric of close texture may be embodied, such as that generally known as tick, these layers or folds being combined in parallelism with the base layer, and said layers or folds together if desired with the overlapping 65 pieces, may be preferably impregnated or

treated with resin, this impregnation or treatment being conveniently effected by rubbing the fabric or other material with the resin either in solid or powdered form, or the resin may be molten and the overlapping pieces and layers immersed in it.

A series of wires may be secured to the aforementioned layers, such wires being secured in close proximity to each other on the 70 respective layers, in such a manner that the wires *c* on the one layer intersect the wires *d* on the other layer, as illustrated by Fig. 5, which, however, for the convenience of the drawing, shows the wires with more space 75 between them than would be the case in practice, while such wires are so arranged of zig-zag or equivalent form along their lengths that no part of the wires of the mesh thus formed are in any way taut, but are capable of a resilient action at any point 80 when struck by a bullet or other missile.

The wires are preferably formed of fine steel springy wire *e* which forms a core to a spiral wire *f* of lesser gage which is wound 85 around the core, and which spiral is preferably not closely coiled, but has a space between each of the coils of the spiral as illustrated by Fig. 9.

These wires are attached closely together 90 so as to cover the face of certain of the layers of the textile fabric and various shapes in the length of the wires other than zig-zag may be substituted, so long as the shape is of such a nature as to allow a certain amount 95 of resiliency at any point which the missile 100 may strike, as for example the wires may take the form of two flattened coils *g*, as illustrated by Fig. 7, the turns of the coils being interlooped. Such a dual coil medium 105 may be attached in lengths to the surface of the fabric.

Instead of the zig-zag or flattened coil media for obtaining the local resiliency, the wires may be attached to the fabric in short lengths, as illustrated by Fig. 6. The said 110 lengths may be arranged in lines, and the spaces between the respective lengths of each line may be located at positions adjacent to mid-points in the wires of the adjacent line or lines so that the said wires 115 and the spaces between the ends thereof are thereby staggered throughout the system. Such a system of wires in one layer may be incorporated with the wires arranged at an angle to the wires of a similar system in 120 another of the layers.

Fig. 8 illustrates an embodiment in which the wire mesh *i* is applied to the fabric of which the layers are composed, this wire 125 mesh being divided at intervals as indicated at *j*.

The section of the core wires may be square, round, or of other suitable shape, and the wires may be woven in with the fabric, and instead of being arranged on 130

the abutting faces of two separate layers of fabric may be arranged on each side of one layer of fabric, while any number of such wire covered layers of fabric may be used.

5 The aforementioned protecting material may be embodied in the form of a garment, to protect any desired portion of the human body, or in the nature of a pad adapted to be disposed as a shield in front of the 10 human body, or at the back, or both the front and back, while in the case of horses, it may take the form of a covering shaped to fit more particularly over the more vital parts of the animal, and in such cases suitable straps may be provided for securing the garment or protector in the required 15 position.

In the case of using the aforementioned protective covering for the protection of, 20 for example, the petrol tanks and engines or other parts of aeroplanes, airships, or motors, the protective covering is so arranged that space is provided between the protective covering and the article which it 25 protects, so as to obviate a hard background or base to the covering, which would form such a solid resistance as would detract from the resilient action of the covering,

and thereby enable the bullet to pierce the covering.

What I claim as my invention and desire to secure by Letters Patent is:—

Bullet proof and like garments or coverings for horses or articles exposed to acts of warfare comprising a base or cover of flexible material to which sets of flaps of flexible material are attached, the flaps in each of said sets being attached at one end only and being attached to said base element at positions substantially close together, the 35 edges of said flap elements, remote from said base element thus terminating substantially together, there being a substantially large number of flap elements in each set, 40 said sets of elements overlapping in such 45 manner that said flexible elements only offer a satisfactory protection all over the surface it is desired to render puncture proof.

In testimony whereof I affix my signature 50 in presence of two witnesses.

JOSEPH PERCY WILKS.
